UNITED STATES PATENT OFFICE

WILLIAM F. PRICE, OF BALA, AND RUDOLPH H. BECK, OF UPPER DARBY, PENNSYLVANIA

BATTERY PLATE FILLING MACHINE

Application filed July 17, 1930. Serial No. 468,650.

This invention relates to machines for filling the openings in a perforate plate with plastic material and more particularly to storage battery cell grids, the machine being an improvement over applicants' Patent 1,757,546 of May 6, 1930.

Such grid plates are usually lead castings presenting a multiple series of narrow elongated rectangular slots, the ribs constituting the partitions, being offset one from another and bevelled outwardly from the median plane of the plate to its side surfaces, these openings being filled with a pasty composition of metallic salts.

Such salts, derived principally from the metal lead, are extremely dangerous to handle, their fine particles being absorbed and inhaled by persons with whom they are brought in contact, constituting an irritant poison.

It is therefore an object of the present invention to provide a machine that accomplishes the work of filling the interstices of grid plates mechanically, with substantially no hand labor, thereby avoiding the danger, and at the same time loss of material by entering the paste directly into the openings without waste.

A further feature is in the provision of means for feeding the plastic, cement-like mass from both sides of the grid plate, coincidentally, whereby the oppositely applied portions are caused to coalesce as a unit becoming firmly locked, feeding taking place only at the grid openings and not at its frame or solid portions.

Another aim is to produce a machine in which a double grid is filled at one operation, the paste being so compacted and pressed as to present a smooth even surface, level and flush with the solid parts of the grid, free from holes or other imperfections and which requires no hand finishing whatever.

These and other meritorious features, as

will later appear, are attained by the novel design, construction and combination of parts hereinafter described and shown in the annexed drawings, constituting an essential portion of this disclosure, and in which:— 50

Figure 1 is a partial rear side elevational view of an embodiment of the invention.

Figure 2 is a transverse sectional view taken approximately on line 2—2 of Figure 1.

Figure 3 is an enlarged fragmentary sectional view taken on line 3—3 of Figure 2, 55 drawn to an increased scale.

Figure 4 is a perspective view of the apertured bed plate through which the paste is forced upwardly.

Figure 5 is a plan view of a double grid plate of the type filled by the machine.

Figure 6 is an enlarged partial sectional view of the grid.

Figure 7 is a longitudinal sectional view 65 of the grid cleaning device, taken on line 7—7 of Figure 8.

Figure 8 is a transverse sectional view taken on line 8—8 of Figure 7.

Figure 9 is a fragmentary sectional view 70 of the scraper and chain.

The bed of the machine, as shown, is composed of a pair of spaced horizontal beams 10 supported at a convenient height and having between them a platen 11 on which the 75 grids G are placed, one by one, and moved forward manually between guides 12.

A flat bar 13 extends across the platen, being adjustably secured at its ends to act as a limiting stop for grids of excessive thickness, normal grids passing below the bar to enter between a pair of corrugated feed rolls 14—15, the former having its periphery substantially level with the upper surface of the platen, it being journaled in bearings extending through the beams and positively driven by sprockets and chain connections with the motive power of the machine.

The upper roll 15 is mounted in bearings adjustable in a housing 16 and pressed down— 90

wardly by compression springs 17, controlled by screws 18, to grip an entering grid, these rolls being geared together to rotate in unison; preferably the circumference of each 5 roll is equal to the length of a single grid so that at each revolution one grid is advanced into the machine.

As the grid is moved forwardly it passes over the surface of a fixed plate 20, level 10 with the platen 11, and having two narrow registering rectangular slots 21 corresponding to the openings G1 on each side of a double grid, the lengths of the slots being arranged to cover the openings G1 and avoid 15 the frame portions G2—G3 of the grids, preventing the paste material from making contact therewith.

A rib 22, centrally of the plate 20, is of a width equal to the grid frame center elements 20 G2, while the plate at the ends of the slots covers the elements G3 and grid ears G4.

Disposed below the plate 20 and extending outwardly through one of the beams 15 is a tubular housing 23, its opposite end 24 being 25 closed.

An upright hopper 25 is open at its bottom to the housing 23 and also open at the top to receive the pasty mass used in filling the interstices of the grid plates.

30 Mounted in the housing 23 is a shaft 26 on which is fixed a helical conveyor having an outer portion 27 of coarse pitch and an inner portion 28 of a much finer pitch, this finer portion extending directly under the slots 21.

35 Journalled in the hopper 25 is a spindle 29 having set at various transverse angles therein a series of mixer arms 30 to stir the contents and assure that the same will enter the coarse portion 27 of the conveyor.

40 The spindle 29 is driven by a pinion 31 on its outer extending end, and meshed with the pinion is a spur gear 32 fixed on the outer end portion of the shaft 26, and outwardly beyond the gear is a sprocket 33 driven by 45 a chain 34 trained over a driving sprocket 35 fixed on the main transverse shaft 36, mounted in bearings 37 below the beams.

On the upper side of the plate 20 is another hopper 38, open at the top and bottom, 50 this hopper being held for height adjustment by side brackets 39 limitedly raised and lowered by nuts engaging studs 40 set in the beams 15.

Rearwardly of the hopper 38 is a rigid 55 arched bracket 42 secured to the beams and having on its face a pair of undercut guide ways 43 in which are adjustably mounted slides 44 having forwardly projecting lugs 45—45' arranged as bearings for upright 60 spindles 46, which extend into the hopper 38, one at each side.

The spindles are provided with adjustable limiting collars 47 resting on the lower lugs 45' and are pressed downward there- 65 against by compression springs 48 encircling

the upper portion of the spindles and exerting thrust on collars 49 fixed thereon.

The spindles 46 are furnished with a plurality of radially extending arms 50, operative within the hopper to stir its contents, 70 and their lower ends have secured to them transversely extending wipers 51 of rectangular cross section so disposed as to present their corners angularly downward, the axes of the spindles being in register with the 75 slots 21, the sides of which are bevelled divergently downwardly.

The length of the wipers 51 is such as to clear the walls of the hopper 38 and also clear a central low partition bar 61, which 80 is fixed in the hopper in register with the rib 22 in the plate 20, these elements acting conjunctively to prevent the paste from being dispensed on the grid center G2 from either side.

85 At the upper end of the spindles 56 are fixed bevel gears 52 meshed with mating gears 53 on the inner ends of horizontal shafts 54 carried in brackets 55 attached by pivoted hinges 56 to the main bracket 42 in such manner as to swing upward out of the way whenever it may be required to remove the slides 44 or spindles 46, as in cleaning, inspecting or repairing the same.

90 On the outer ends of the shafts 54 are fixed sprockets 57 driven by chains 58 trained around sprockets 59 fixed on the main shaft 36, and, due to the brackets being hinged, upon releasing bolts 60, clamping the brackets in fixed operative position, the upright 95 spindles and associated parts are rendered readily accessible.

100 The right hand element 51 presses the paste against the forward ribs of the grid and the left hand element presses the paste 105 against the rear ribs, and, due to the angularity of these elements and right and left hand motion, the pasting is uniform, presenting a smooth level surface.

105 Rearwardly of the pasting devices are a 110 pair of shafts 65—66 journalled in brackets at the lower portions of the beams 10 to extend outwardly in spaced relation, one of the shafts, as 65, having on its rear end a sprocket 67 driven by a chain 68 from some 115 convenient rotative part of the machine.

120 A pair of brackets 69—69', fixed on the beams 10, carry adjustable bearings in which are mounted another pair of shafts 70—71 directly above the shafts 65—66.

125 On the front end of the shaft 66 is a spur gear 72 meshed with a mating gear 73 revolvable on a stud 74 fixed in the adjacent beam and secured to the outer side of the gear is a sprocket 75 driving a chain 76 trained over another sprocket 77 fixed on the end of the shaft 71.

130 Fixed on the shafts 65—66, adjacent the inner sides of the beams 10, are sprockets 78—79, over which are trained chains 80; 135

similar sprockets 81—82 are fixed on the upper shafts 70—71, over which are trained chains 83, these sprockets and chains being in pairs as will readily be seen.

5 Disposed at spaced intervals in the links of the chains, are carrier links 84 connected from side to side of the machine by bars 85 of triangular cross sections, see Figure 9, and fixed on the angular faces of the bars 10 are inner and outer plates 86—87 having between them strips 88 of thin sheet steel.

These wiper strips are thus carried at an approximate angle of forty-five degrees with the faces of the grids G passing therebetween 15 as best seen in Figure 7.

The length of wiper strips is such as to pass freely between side bars 89 and the lower strip is cut away to avoid contact with a center bar 89'.

20 It is to be noted that the wipers move in the same direction as the passing grids but at a very considerably increased speed, and also that the wipers act on opposite sides of the grids simultaneously.

25 Means, as the adjustable blades 90, are provided to scrape one of the surfaces of the wipers, while a similar blade 91 removes any adherent débris from the opposite side as the chains are advanced. A like blade 92 30 is provided for the lower series of scrapers, all of which appear in Figure 7.

Finally, after the grids have passed onward beyond the scope of the scrapers, they are caused to pass between a pair of opposed, 35 angularly positioned scraper blades, 93—94 mounted on the track, these blades smoothing and levelling any irregularities whatever, the detritus dropping into a container 45 conveniently positioned to receive the 50 same.

As changes of construction could be made within the scope of the invention, it is intended that all matter contained in the foregoing description or shown in the accompanying drawings shall be interpreted as 55 illustrated and not in a limiting sense.

Having thus described the invention, what is claimed as new and desired to secure by Letters Patent, is:—

0 1. A battery grid pasting machine for double grids, comprising a horizontal platen, a pair of feed rolls to advance a grid therebetween over said platen, an adjustable bar to prevent the passage of an abnormally 5 thick grid, a plate set in said platen having two narrow openings corresponding in length to the length of the apertured portions of the double grid, two independent paste hoppers, means associated with one of said 10 hoppers for feeding paste upwardly through the openings in said plate, and adjustable means combined with the other hopper to smooth the paste entered therefrom on the upper side of said grid.

5 2. A battery grid pasting machine for dou-

ble grids, comprising a horizontal platen including a plate having two narrow transverse registering slots, each slot being equal in length to the apertured portions of the double grid, means for advancing the grids 70 over said plate, means for partially filling the grid apertures through said slots from the under side of said plate, stirring means above said plate to complete the filling of the grid apertures, and means for smoothing the 75 upper surface of the grid while passing over a level unbroken portion of said plate.

3. A battery grid pasting machine for double grids, comprising a horizontal platen, a pair of feed rolls to advance a grid there- 80 along, adjustable means to prevent the passage of an abnormally thick grid, a plate set in said platen having two narrow openings corresponding in length to the length of the apertured portions of the double grid, two 85 independent paste hoppers, a tubular casing extending below and in communication with one of said hoppers, a screw conveyor rotatable in said casing to deliver paste upwardly through said opening to partially fill the 90 grid interstices, means in the other hopper to completely fill the grids, a longitudinal rib at the bottom of the hopper in register with the connection between the portions of the grid to prevent depositing paste on the connection, and rotatable means in said hopper to finish the surface of the grids, said finishing means being positioned on the axis of the under feeding means.

4. A battery grid pasting machine for 100 double grids, comprising a horizontal platen, a pair of feed rolls to advance a grid there- 105 on, adjustable bar means to prevent the passage of an abnormally thick grid, a plate set in said platen having two narrow openings corresponding in length to the length of the apertured portions of the double grid, two 110 independent paste hoppers, a tubular casing extending below and in communication with one of said hoppers, a screw conveyor rotatable in said casing to deliver paste up- 115 wardly through said openings to partially fill the grid interstices, said screw conveyor having a variant pitch progressively finer to- 120wards its discharge end, rotary means in the other hopper to compact and smooth the paste fed therefrom to the upper surface of the grids, resilient means for pressing said rotary smoothing means downwardly, and means for adjusting said resilient means.

5. A battery grid pasting machine for double grids, comprising a horizontal platen having a pair of registering transverse slots substantially equal in length to the zone of openings in the double grid and of a width commensurate to the width of the openings, a paste hopper at the side of the machine, a helical conveyor of progressively increasing pitch to force paste from said hopper into 125 said slots to partially fill the opening in the 130

grids as passed thereover, a second hopper over the path of the grids to finish filling the openings therein, a pair of upright spindles rotatable in the second hopper, and means on the lower extremities of said spindles to press and smooth the paste level with the solid portions of the grid.

6. In a grid filling machine having a horizontal platen, a paste hopper adjustable thereover, a pair of upright spindles extending into said hopper, means for filling paste into grids passing over said platen from the under side thereof, other means on said spindles to complete the filling operation from the upper side of the grids, gear drives for said spindles, and brackets hinged on opposite sides of the machine carrying said drives permitting them to be swung into and out of operative position allowing the spindles and parts therein to be removed intact.

7. In a grid filling machine having a horizontal platen, independent paste hoppers at the side and above said platen respectively, a helical conveyor of progressively increasing pitch to force paste from the side hopper into the grids when moving over said platen in advance of the other hopper, said last named hopper being located over the platen in register with the under filling means, and rotative paired elements in the last named hopper to compact paste fed therefrom, causing coalescence with the paste fed from below, said paired elements smoothing the upper surfaces of the grids, the lower surfaces of which are smoothed by contact with the level surface of the platen over which they pass.

8. In a grid filling machine having a platen at the front and a track-way at the rear, means for advancing a double grid over the platen and track-way, means for filling the interstices of the grids from both sides while passing over said platen, a pair of spaced endless conveyor chains movable below said track-way, triangular bars connecting between said chains their oblique faces being directed rearwardly to the movement thereof, inner and outer clamp plates on the oblique faces of said bars, and flat spring brush plates fixed between said clamp plates to contact the under surface of the grids when moving over the track-way, said chains travelling at a higher rate of speed than the grids.

9. In a grid filling machine having a platen at the front and a track-way at the rear, means for advancing a double grid over the platen and track-way, means for filling the interstices of the grids from both sides while passing over said platen, a pair of spaced endless conveyor chains movable below said track-way; a second pair of similar chains movable above said track-way, triangular bars connecting between each pair of said chains at spaced intervals therealong their oblique faces being directed rearwardly

to the movement thereof, inner and outer clamp plates on the oblique faces of said bars, and flat spring brush plates fixed between said clamp plates to contact the both surfaces of the grids when moving over the track-way, said chains travelling at a higher rate of speed than the grids.

In testimony whereof we have affixed our signatures.
